UNITED STATES PATENT OFFICE.

ALBERT FALKENRATH, OF RACINE, WISCONSIN.

SPRING-HINGE.

No. 824,923.

Specification of Letters Patent.

Patented July 3, 1906.

Application filed July 31, 1905. Serial No. 272,026.

To all whom it may concern:

Be it known that I, ALBERT FALKENRATH, a citizen of the United States, residing at Racine, in the county of Racine and State of Wisconsin, have invented new and useful Improvements in Spring-Hinges, of which the following is a specification.

My invention relates to spring-hinges, and particularly to double-acting spring-hinges, and has for its principal object the provision of such a hinge in which certain of the parts are made from sheet metal and in which the wearing of the parts due to friction shall be reduced to a minimum.

15 A further object is to provide a hinge in which the parts may be readily assembled and are accurately centered when assembled.

The invention consists in the novel features of construction and combination of parts hereinafter described and claimed, and shown in the accompanying drawings, which illustrate a preferred embodiment of the invention.

25 In the drawings, in which like reference characters designate corresponding parts throughout the various figures, Figure 1 is a view in cross-section, taken on line 1 1 of Fig. 2 and showing the construction of my improved hinge. Fig. 2 is a side elevation of the same with one wing opened at a right angle to the intermediate web, part of said web being broken away and one barrel shown in vertical longitudinal section. Fig. 3 shows a side leaf of the hinge in elevation. Fig. 4 is a detached view of the central web. Fig. 5 is an end view of the same. Figs. 6 and 7 show the pintle-sockets with their spring-slots and their securing and adjusting 35 pin-holes. Fig. 8 shows a modified form of lower pintle-socket.

Referring to the drawings, 1 and 2 designate the parts to be hinged together, which may be a door and door-jamb, respectively. 45 The hinge is composed of two side leaves 3 and 10 and a central leaf or web 5. Each of the side leaves 3 and 10, which are preferably similar, is formed from a sheet of metal folded upon itself to provide barrels 50 8 9 and a flat leaf portion proper. The leaf portions proper are preferably strengthened by a stiffening strip 3'', which is placed between the folds of the leaf, and both it and the folds are perforated, as shown, to receive 55 screws 3' 4 for attachment to the door and door-jamb. The intermediate leaf or web

5 consists of a substantially rectangular plate carrying four projecting lugs or winged seats 6 7 and 6' 7', between which the barrels 8 and 9 are supported. The lugs are made 60 integral with the plate, the whole being preferably one casting, although it may be made of sheet metal with the lugs "slotted on."

At least one connection between the bar- 65 rel and the wings of the central web consists of the pintle-socket and spring-holder 11 and sleeve 16, (shown enlarged and detached in Fig. 7, where it will be seen that the pintle-socket is formed with a reduced portion 15, 70 formed with a slot 12 to receive the end of spring 13 and a base portion 18.) Sleeve 16 is perforated to fit and move freely about reduced portion 15 of pintle-socket and spring-holder 11 and has a portion formed 75 to fit snugly within the barrel 9 and a flange 17, which constitutes a seat for the barrel, and has an external periphery flush with the peripheries of the barrel 9 and base 18 of the pintle-socket and spring-holder 11. 80

The base 18 of the pintle-socket 11 is pro- 85 vided with holes 19 for the reception of an adjusting-tool and a retaining-pin 20. This pin 20 when spring 13 is tensioned by turn- 90 ing the pintle-socket and spring-holder rests against the central leaf or web 5, as shown in Figs. 1 and 2, and forms the means of ad- justment according to which of the holes 19 it occupies.

The upper pintle-socket and spring holder 90 21 has a slotted part 22 for the reception of the upper end of spring 13, the flange 23 be- 95 ing turned so as to fit snugly into the barrel, in the upper end of which it is firmly secured by a pin 24, passing through a hole in the barrel-shell and into the hole 25 in the socket. The base 18 of the lower socket rests upon 100 the wing 7', and the base 23 of the upper socket abuts against the under side of and flush with the edges of wing 6', the barrel 105 completely inclosing the upper socket and fitting flush with the base of wing 6', while the lower end of the barrel rests upon the flange 17 of sleeve 16, so as to fit flush with wing 7'. The object of the lower pintle- 110 socket and spring-holder and sleeve-con- struction is to provide an efficient bearing other than the barrel itself, so that when worn one or both of these parts may be readily removed and replaced with very little trouble and expense. This form of con- nection may also be employed in place of the

upper pintle-socket, if desired. The wings extend out from the plate 5 just far enough to give the barrels a working fit, thus leaving as little of the hinge exposed as possible.

5 In assembling the hinge the ends of the spring are slipped into the slots formed in the sockets. Then the barrel is slipped over the spring with its lower end resting on the flange 17 of sleeve 16, after which socket 21 is secured to barrel 9 by pin 24. Then the barrel is slipped in between the winged seats 6' 7', and pintle 26 is run through the perforations formed in the wings and pintle-sockets and through the spring. Finally, the knobs 27 10 are placed thereon, one above wing 6' and the other below wing 7', and the pintle is upset on said knobs, so as to hold the parts firmly 15 together.

While I have described a sleeve upon which 20 the barrel is supported to give it a better working surface on the pintle-socket, it is obvious that the barrel may rest upon a shoulder cut in the socket itself, as shown in Fig. 8. Likewise the stiffening-strip between the 25 folds of the side leaves may be omitted and various minor changes may be made without departing from the spirit of my invention.

Having described my invention, what I 30 claim as new, and desire to secure by Letters Patent of the United States, is—

1. In a spring-hinge, a leaf adapted to be connected to a part to be hinged and formed from a sheet of metal folded upon itself to provide a barrel, a coöperating leaf having 35 projecting wings between which said barrel is secured, a pintle-socket and spring-holder at one end of said barrel engaging one of said

wings and formed with a reduced portion within the barrel and a base, a sleeve upon said reduced portion and bearing upon said base, said sleeve being formed with a flange engaged by the barrel, a second pintle-socket and spring-holder at the opposite end of said barrel, a pintle securing said parts in operative position, an actuating-spring constructed to engage said pintle-sockets and spring-holders within said barrel, and operative connections between the parts, substantially as described. 40 45

2. In a double-acting spring-hinge, leaves 50 adapted to be connected to the parts to be hinged and each formed from a sheet of metal folded upon itself to provide a barrel, a central leaf or web having projecting wings between which said barrels are secured, a 55 pintle-socket and spring-holder at one end of said barrel engaging one of said wings and formed with a reduced portion within the barrel and a base, a sleeve upon said reduced portion and bearing upon said base, said sleeve being formed with a flange engaged by a barrel, a second pintle-socket and spring-holder at the other end of said barrel, a pintle securing said parts in operative position, an actuating-spring within said barrel constructed to engage said pintle-sockets and spring-holders, and operative connections 60 between the parts, substantially as described. 65

In testimony whereof I affix my signature in presence of two witnesses.

ALBERT FALKENRATH.
